JACOB GOLDBERG, OF CINCINNATI, OHIO, ASSIGNOR TO THE GOLDBERG PADDING MACHINE COMPANY, OF CINCINNATI, OHIO, A CORPORATION OF OHIO.

CLOTH-FEED MECHANISM FOR BLINDSTITCH SEWING-MACHINES.

1,352,061.

Specification of Letters Patent. Patented Sept. 7, 1920.

Application filed September 3, 1919. Serial No. 321,372.

To all whom it may concern:

Be it known that I, JACOB GOLDBERG, a citizen of the United States of America, and a resident of Cincinnati, in the county of 5 Hamilton and State of Ohio, have invented a new and useful Improvement in Cloth-Feed Mechanism for Blindstitch Sewing-Machines, of which the following is a specification.

10 My invention relates to a machine which may be used either for blind-stitching or for felling. In the former it is necessary for the bridge to project well into the feed slot of the table so that the needle will take 15 a deep stitch so as to pass into all the layers of the goods. In the latter it is necessary for the bridge to project to a less amount into the feed slot so that the needle will pass into only the two upper layers of the 20 cloth, and only to a small depth into the lower of these layers.

In factories the change from one to the other of these operations is frequent, and heretofore the change of the feed mechanism was a nice adjustment, which required 25 the use of considerable skill upon the part of the operator.

It is the object of my invention to provide a bridge which may be changed from 30 a blind-stitching to a felling position, quickly and without any manipulation.

This object is attained by the means described in the specification and illustrated in the accompanying drawings, in which:—

35 Figure 1, is a front elevation of the table and the feed mechanism of a blind-stitch sewing machine and of a bridge construction embodying my invention.

Fig. 2, is a sectional view taken upon 40 line 2—2 of Fig. 1.

Fig. 3, is a side elevation of a set screw forming a detail of my invention.

Table A is provided with the usual longitudinal feed slot a, feed rolls B, and support 45 D for the feed rolls.

Support D has two lugs d between which is mounted a pin e upon which the rear end of bridge E is pivoted. In longitudinal alignment with lugs d are two lugs d', d" 50 between which extend the forward end of

bridge E, which terminates in finger piece e'. A curved slot e² is formed in the bridge, with pivot e as its center of curvature. Slot e² is adapted to pass the reduced end g of set screw G which is seated in a screw 55 threaded transverse bore in lug d'. Slot e² is of a length such that when its upper end contacts with end g, the bridge is in position for felling, and when its lower end contacts with the end g, the bridge is in 60 position for blind-stitching, with the ordinary thickness of cloth.

Hence in operation the change of the bridge is made by loosening the set screw, pushing the bridge to either of its limits and 65 resetting the screw.

Having thus described my invention, what I claim is:—

1. In a machine of the class described the combination of a support, a bridge pivoted 70 at one end to the support, and having in its opposite end a slot, and a set screw mounted in the support and having a reduced end passing through the slot, the slot and the reduced end being adapted to limit 75 the movement of the bridge and being so proportioned that at one limit of movement of the bridge the machine is adapted for felling and at the other limit of movement is adapted for blind-stitching. 80

2. In a machine of the class described the combination of a bridge support having a pivot pin upon the support, spaced lugs upon the support opposite the pivot, a bridge mounted upon the pivot movable 85 thereon between the lugs and having a slot adjacent to the lugs, and a set screw mounted in one of the lugs and having a reduced end engaging the slot, the slot and the reduced end being adapted to limit the movement of 60 the bridge and being so proportioned that at one limit of movement of the bridge the machine is adapted for felling and at the other limit of movement is adapted for blind-stitching. 95

In testimony whereof, I have hereunto subscribed my name this 2nd day of September, 1919.

JACOB GOLDBERG.
